UNITED STATES PATENT OFFICE.

CHARLES C. WORTHINGTON, OF IRVINGTON, NEW YORK.

DESIGN FOR A DUPLEX STEAM-PUMP FRAME.

SPECIFICATION forming part of Design No. 30,496, dated April 4, 1899.

Application filed September 29, 1898. Serial No. 692,233. Term of patent 14 years.

To all whom it may concern:

Be it known that I, CHARLES C. WORTHINGTON, a citizen of the United States, residing at Irvington, county of Westchester, and 5 State of New York, have invented and produced a certain new and original Design for a Duplex Steam-Pump Frame, fully described and represented in the following specification and the accompanying drawings, forming a part of the same.

This invention relates to a new and original design for a duplex steam-pump frame; and the invention consists in a peculiar shape or configuration of such a frame, substantially as shown in the accompanying drawings, in which—

Figure 1 is a side view of a duplex steam-pump frame embodying the design. Fig. 2 is a plan view of the same. Fig. 3 is a perspective view of the same, looking from the water end.

The leading feature of the design is the peculiar shape or configuration of the steam-cylinder and water-end portions of the frame, 25 in connection with the connecting-frame or cradle portion made harmonious in design with the steam and water ends, and in which the steam-cylinders A curve outward from the base of the narrower single steam-chest and

steam-port portion B and develop into the 30 cradle-bars C, connecting the steam end to the water end, and with the pump-cylinders D curving outward from the base of the single - pulsation and valve chamber E, with force-chamber E' upon the chamber E and 35 with the suction connection F and force connection G formed as shown.

The cylinders A are shown as formed with flanges H at their outer ends and the pump-cylinders D with flanges I at opposite ends, 40 into which the pulsation and valve chamber E develops, and both the steam and pump end are shown as provided with supports J, by which the pump-frame is mounted on the bases K. The usual piston and valve-rod 45 stuffing-boxes L are shown, and upon the top cradle-bar C is mounted the valve-motion bracket M.

What I claim is—

The design for a duplex steam-pump frame, 50 substantially as shown and described.

In testimony whereof I have hereunto set my hand in the presence of two subscribing witnesses.

CHARLES C. WORTHINGTON.
